UNITED STATES PATENT OFFICE

2,355,853

METHOD OF HOLDING DIAMONDS FOR DRILLING

Henry James Foxon, Wembley, England, assignor to General Electric Company, a corporation of New York

Application March 16, 1942, Serial No. 434,977
In Great Britain April 16, 1941

5 Claims. (Cl. 22—202)

My invention relates to the manufacture of diamond dies. In such manufacture one stage usually consists in fixing the diamond to be drilled in a recess in a steel block or like holder so that it lies over a perforation in the holder. The fixing must be extremely firm and allow of no possibility that the diamond may move relatively to the holder in subsequent operations; and the position of the diamond relatively to the perforation must be adjustable with considerable accuracy.

In one common method, the diamond is held in the recess between the points of two needles, one of which passes through the perforation; the holder is heated and liquid metal is poured into the recess. At a suitable stage in the cooling of the holder and metal, the added metal is rammed home by a press or the like. This last step is necessary, because otherwise gas trapped in the metal is apt to imperil the permanence of the fixing; but it is difficult to ensure that the diamond, supported only by the needles, does not shift during the step. Moreover since the holder has to be heated, the diamond is apt to be partly burned away.

An object of this invention is to provide an improved method of fixing the diamond in the holder, as well as a novel assembly for holding the diamond.

According to the invention the diamond is fixed, by a method that does not require the raising of its temperature, into a carrier which fits closely into the aperture in the holder; the said carrier is introduced into the aperture; the assembly, to which may be added one or more subsidiary members (for example as hereinafter described), is introduced into an evacuated space; and liquid metal is introduced into the aperture so that, when cold, it fixes the diamond firmly in the holder.

One method according to the invention will now be described by way of example with reference to the accompanying drawing, wherein Figure 1 shows the holder at (a), the carrier at (b), and a subsidiary member at (c), these parts being unassembled; Figure 2 shows on a larger scale a plan view and side section of the said carrier with the diamond fixed in it; Figure 3 shows an elevation, partly in section, of these parts immediately prior to their assembly; Figure 4 shows an elevation, partly in section, of the assembly in the evacuated space with the metal that is to be melted in position, but still unmelted.

The holder 1 is of the usual kind, being a steel disc with an aperture 2 having a perforation 3

at the bottom. The metal carrier 4 is a dished disc slightly wider than the aperture or cavity 2 and provided near its apex with radial claws or fingers 5 adapted to grip the diamond. The subsidiary member 9 is a steel ring fitting easily into the aperture.

In assembling the parts the carrier is placed over the aperture; the diamond 6 is held in the center of the carrier, between the claws, by needles 7, one of which passes upwards through the perforation 3 and the other projects downwards from above. A plunger 8, whose end is similar to the subsidiary member 9, is then brought down, so as to press the carrier 4 into the aperture 2; at the same time, owing to the shape of the carrier, the claws 5 grip the diamond firmly. The plunger is then withdrawn and replaced by the member 9.

A piece 10 of suitable alloy or solder having a low melting point (that generally used in the known method will serve) is then placed in the ring 9, and the whole assembly is introduced into the silica vessel 12, which is then evacuated. The assembly is then heated by high frequency induction from a coil (not shown) placed round the vessel, so that the metal 10 melts and flows round the diamond. The assembly is then allowed to cool and removed from the vessel.

The holes 11 in the base of the claws of the carrier (see Figure 2) are provided in order that the metal may easily flow through the carrier. They are placed so that the ring 9, when in place, leaves most of them uncovered. Metal passing through the holes may get between the diamond 6 and the perforation 3, but this does not matter since it is drilled away after the fixing is complete.

In Figure 3 the concave side of the carrier is downwards. This is preferable if the diamond is relatively thick. If it is relatively thin, it may be preferable to place the concave side upwards during the step shown in Figure 3.

What I claim as new and desire to secure by Letters Patent of the United States is:

1. The method of fixing an unperforated diamond, preparatory to drilling it, in a holder having a cavity therein and an aperture communicating with said cavity, which comprises fitting the diamond in a carrier member which firmly engages the periphery of the diamond and fits securely in the cavity, clamping the diamond between opposed needles one of which extends through the said aperture in the holder, moving the needles longitudinally to carry the diamond into the cavity against the periphery of the said

aperture while pressing the said carrier member into engagement with the walls of the cavity to thereby center the diamond and firmly support it in place, withdrawing the said needles, and then flowing molten metal into the cavity around the diamond and the carrier member.

2. The method of fixing a diamond in a cavity in a holder also having a small aperture therein communicating with said cavity, preparatory to drilling the diamond, which comprises placing the diamond in an opening formed by the ends of radial claws at the center of a disc-like carrier which fits closely in said cavity, pressing said carrier into said cavity so that said claws grip the diamond and hold it firmly in place therein in alignment with said aperture, placing the assembly in an evacuated space, and introducing molten metal into said cavity around said diamond to fix it in place and firmly hold the parts of the assembly together.

3. The method of fixing a diamond in a cavity in a holder also having a small aperture therein communicating with said cavity, preparatory to drilling the diamond, which comprises placing the diamond in an opening formed by the ends of radial claws at the center of a dished disc-like carrier which fits closely in said cavity, pressing said carrier into said cavity so that the rim of the carrier is flattened against the bottom of the cavity and said claws grip the diamond and hold it firmly in place therein in alignment with said

aperture, placing the assembly in an evacuated space, and introducing molten metal into said cavity around said diamond to fix it in place and firmly hold the parts of the assembly together.

5 4. In an assembly for holding a diamond to be drilled, a holder having a cavity therein and a small aperture communicating with said cavity, a carrier member which fits closely in said cavity and grips said diamond to hold it firmly in place
10 in said cavity, said carrier member comprising a disc having radial claws extending toward an opening at the center of the disc and gripping the diamond to hold it in said opening in alignment with said aperture, and a cast metal filling in said cavity serving to encase the diamond and carrier and firmly hold the parts of the assembly together.

15 5. In an assembly for holding a diamond to be drilled, a holder having a cavity therein and a small aperture communicating with said cavity, a carrier member which fits closely in said cavity and grips said diamond to hold it firmly in place in said cavity, said carrier member comprising a normally dished disc having radial claws extending toward an opening at the center of the disc and gripping the diamond to hold it in said opening in alignment with said aperture, and a cast metal filling in said cavity serving to encase the diamond and carrier and firmly hold the parts of the assembly together.

HENRY JAMES FOXON.
